UNITED STATES PATENT OFFICE.

WARREN R. COX, OF CLEVELAND, OHIO.

SAFEGUARD FOR ELECTRIC CIRCUITS.

1,378,659.

Specification of Letters Patent. Patented May 17, 1921.

Application filed October 1, 1917. Serial No. 194,116.

To all whom it may concern:

Be it known that I, WARREN R. Cox, citizen of the United States, residing at Cleveland, in the county of Cuyahoga and State of Ohio, have invented certain new and useful Improvements in Safeguards for Electric Circuits, of which the following is a specification.

My invention relates to means for safe-guarding automobiles or other vehicles employing an electric ignition system for an internal combustion engine, and the invention is an improvement on the safety device shown and described in my application for Letters Patent, filed November 13, 1915, Ser. No. 61,263 now Patent No. 1,253,470. In said application, a switch and a plurality of spark coils are locked by a common means to prevent theft of the automobile, and my present conception is to provide the switch with an auxiliary device, whereby all the spark coils are grounded when the switch is turned off, thus preventing an operative electrical circuit from being obtained by wires attached to the terminals exposed at the rear of the coil box. Briefly, it has been possible heretofore to ground one of the spark coils and establish a working circuit on the other coils so that a multiple cylinder engine could be operated on a sufficient number of its cylinders to permit the theft of the machine under certain circumstances.

In the accompanying drawings, Figure 1 is a front view of a coil box partly broken away, and showing a switch embodying my improvement. Fig. 2 is a front view of the switch with the locking plate removed. Fig. 3 is a vertical section centrally through the coil box and lock-switch. Fig. 4 is a side elevation, and Fig. 5 a front view, of the coil box and switch as it appears secured to the dash of a vehicle. Fig. 6 is a horizontal section in plan of the coil box and dash and the lock switch. Fig. 7 is an electrical diagram of an ignition system embodying my improvement.

The invention comprises a metal box 2 which is secured to the dash 3 of a vehicle by bolts 4, and also by screws 5 which are accessible only when the sparking units 6 containing the induction coils are removed from the metal box 2. Each unit 6 has a set of contacts to provide electrical connection with the terminal posts 7 fixed to dash 3 and also electrical connection with a bus bar 8 within the bottom of the box. These units

are removably seated within the box and are locked in place by a screw 9 which extends through the base 10 of the electrical switch 11 at the front of the box. The head of 60 screw 9 and the switch are inclosed by a metal cover 12 carrying a Yale or equivalent lock 13 requiring a key 14 to operate it to switch the electric current on and off and also to permit removal of the cover. The switch 65 comprises a rotatable arm having a metal segment 15 adapted to bridge and contact with the spring contacts 16 and 17, respectively, when given a partial rotative movement clockwise from the neutral or off position shown in the several figures of the drawings. A metal locking plate 18 is screwed to base 10 at the front of the switch arm, and a notched arbor 19 projects through this plate and is detachably engaged with a flat T-blade 20 extending from the rear end of rotatable cylinder of lock 13. That is, blade 20 may be disengaged from plate 18 when its T end registers with the radial notches 21 in the plate, but not otherwise, and when locked together as shown in Fig. 3, the cover 12 cannot be removed nor the switch operated without key 14. To prevent the operation and use of one or more of the spark coils or units 6 by unauthorized persons who may have sufficient knowledge of the wiring circuits to wire the exposed terminals and establish a working circuit to operate the engine in part, I have provided the apparatus above described with means to 90 ground each and all of the coils or sparking units 6 by means of a coiled spring 22 adapted to be engaged by the switch segment 15 in its off or neutral position, see Figs. 2 and 6. This spring is sleeved loosely 95 on a metal bolt 23 which extends through plate 18 at one side of switch segment 15, and a nut 24 secures this bolt to the metal box 2, in this way establishing an electrical circuit to the ground through the box and a 100 piece of metal 25 at the rear thereof where affixed by one of the bolts 4 to the dash 3. Grounding of the box and piece 25 is through the frame of the engine or other part of the machine, my aim being to ground 105 the primary circuit through line 29 in the same way as the secondary circuit 30 containing spark plugs 26 is grounded, see Fig. 7, which shows the four units 6 electrically connected with said elements and the switch, 110 and also shows the bus bar 8 for all the units grounded through wire 29, segment 15,

spring 22, box 2 and piece 25. The bus bar is confined within box 2 beneath the units and cannot be reached until screw 9 is removed, but this screw cannot be reached except when plate 18 and cover are removed. However, cover 12 cannot be removed nor the switch turned to break the ground connection between segment 15 and spring 22, without the use of key 14. Therefore, the single locking means employed, safeguards the operation of the switch, access to the operating parts of the switch and the grounding device as well as the locking screw 9 for the units, in this way preventing removal and theft of the coils or units 6 and access to the bus bar 8 and contacts. Grounding of the primary circuit under lock and key as described defeats any attempt to wire one or more of the units at the exposed terminals 7, thereby preventing the operation and theft of the vehicle, the main purpose of the invention.

What I claim is:

1. A coil box, sparking units removably mounted in said box, an electric switch and means for establishing and grounding an electric circuit for said units, and key-controlled mechanism to operate said switch and prevent removal of said units from said box.
2. A box having a plurality of electrical sparking units removably secured therein, an electric switch and means to place said units in an electrical circuit and to ground said units when out of circuit, and a key-controlled locking device to prevent the operation of said switch.
3. An electrical circuit and a set of spark coils and an electric switch therein and means to ground the spark coils in said circuit, and a common means to lock the switch and coils and grounding means to prevent a working circuit from being established.
4. A plurality of spark coils and a container therefor, an electric circuit for said coils having a switch to establish a working circuit and to ground the coils, a cover to inclose said switch, and a single locking means to prevent operation of said switch and removal of said cover and the coils.
5. In combination, a plurality of sparking coils and a box therefor, an electric switch to establish a working circuit for said coils, means to ground said coils when the switch is in an off position, and a key-controlled mechanism for locking said switch and securing said coils within said box.
6. In combination, a box and a plural number of sparking coils therein, an electric switch to control the operation of said coils mounted upon the box, means to secure the coils within the box, a grounding device for the coils, a cover inclosing said switch and securing means and the grounding device, and a key-controlled mechanism adapted to operate said switch and lock said cover.

7. A plurality of spark coils, a container for said coils, means to lock the coils in the container, an electric switch to control the use of the coils mounted upon said container, a grounding device for the coils controlled by said switch, a cover inclosing said switch and device and the locking means for the coils, and a lock and key adapted to operate said switch and secure said cover in place to prevent access to the parts inclosed thereby.

8. A plurality of spark coils and a box therefor, a switch to place said coils in an electric circuit, a locking plate at the front of said switch, a circuit grounding device for said switch, a cover inclosing said switch and device and said plate, and a lock carried by said cover having operating connection with said switch.

9. A coil box having a plural number of sparking coils removably mounted therein, a switch base secured to said box having a switch in electrical connection with said coils, a grounding device for the coils operant by the movement of the switch, a locking member for the coils extending through the switch base, a cover for the switch and said locking member, and a key-controlled lock for the cover in operant engagement with the switch.

10. A box having contacts in the wall thereof, a plurality of sparking units seated within said box in engagement with said contacts, a locking element to secure said units within the box, an electric switch mounted upon the box in electrical connection with a contact for each unit, an auxiliary contact for the switch to ground the electrical connection for said sparking units, a cover to inclose said switch and locking element, and a lock and key for said cover having operant connection with the switch.

11. In means for safeguarding an automobile, spark coils, an electric circuit, a key-controlled lock switch to place said coils in said electric circuit, and means adapted to ground the spark coils upon turning the switch off.

12. In combination, a plurality of spark coils having a primary circuit provided with means to ground the same, and a key-lock adapted to control the operation of said circuit-grounding means.

13. In combination, an electric circuit having a source of electric current, coils in said circuit, a switch in said circuit, and a device for grounding the coils to render them inoperative when the switch is thrown open.

14. In combination, an electric ignition circuit having a switch adapted to open and close the circuit, and means associated with the switch adapted to ground the electric current upon opening the switch.

15. In means to safeguard an automobile, an electric ignition circuit having coils and

- ignition devices and a magneto therein, a switch for said circuit, and a circuit grounding device adapted to be engaged by said switch when thrown open.
- 5 16. An ignition circuit for an automobile engine, a key-operated switch for said circuit having a movable contact member, and a circuit grounding device adapted to be engaged by said contact member in an open position of said switch.
- 10 17. An ignition circuit in an automobile having coils and ignition devices and a magneto and a switch for connecting the magneto to the coils, said switch being adapted 15 to occupy a neutral position and break the circuit from the magneto to the coils, and a device coöperating with said switch adapted to ground the circuit when the switch is in neutral position.
- 15 18. The combination with a lead from a source of current, of an ignition circuit, a switch for controlling the connection between the ignition circuit and the source of 20 current, said switch having an operative and a neutral position, and a member automatically adjusted by movement of the switch to neutral position for grounding the current in case the connection is made from the source of current to the ignition system without getting through the switch.
- 25 19. The combination with the ignition circuit of an automobile or the like including the coils, ignition devices electrically connected thereto, a magneto or the like, a switch for connecting the magneto to the 30 coils, said switch having a neutral position wherein the circuit from the magneto to the coils is broken, and an intercepting device adjusted by the switch to neutral position for grounding the magneto lead whenever 35 an attempt is made to operate the ignition circuit when the switch is in neutral position.

Signed at Cleveland, in the county of Cuyahoga, and State of Ohio, this 21st day of September, 1917.

WARREN R. COX.
